UNITED STATES PATENT OFFICE.

ORAL C. ZUCK AND LEE O. BACON, OF OKMULGEE, OKLAHOMA.

ROPE OR CABLE CLAMP FOR WELL-DRILLING RIGS.

1,359,013.

Specification of Letters Patent. Patented Nov. 16, 1920.

Application filed April 9, 1920. Serial No. 372,589.

To all whom it may concern:

Be it known that we, ORAL C. ZUCK and LEE O. BACON, citizens of the United States, residing at Okmulgee, in the county of Okmulgee, and State of Oklahoma, have invented certain new and useful Improvements in Rope or Cable Clamps for Well-Drilling Rigs; and we do hereby declare the following to be a full, clear, and exact description of the invention, such as will enable others skilled in the art to which it appertains to make and use the same.

The object of the invention is to provide a simple and strong and efficient rope or cable clamp adapted for relative adjustment of the gripping jaws to adapt it to different diameters of rope or cable and for different conditions and materials composing the rope or cable to resist variations in strain which may be applied thereto, and with this object in view the invention consists in a construction and combination of parts of which a preferred embodiment is shown in the accompanying drawings, wherein—

Figure 1 is a plan view of the clamp showing the same in engagement with a rope or cable.

Fig. 2 is a side view of the same.

Fig. 3 is a longitudinal section on the plane indicated by the line 3—3 of Fig. 2.

Fig. 4 is a plan view partly in section showing the clamp open.

Fig. 5 is a perspective view of one of the die members.

The device consists essentially of the jaws 10 provided with eyes or loops 11 with which may be connected links 12 for attachment to cables or chains by which the clamp is supported, said jaws being slotted as indicated at 13 for the reception of retaining disks 14 to which the jaws are pivoted as at 15, the inner faces of the jaws being provided with toothed segments 16 which are in mesh to insure a mutual or joint swinging movement of the jaws as they are opened and closed, and to insure the registration when the jaws are closed of the die seats 17 formed transversely in the meeting faces thereof. In these die seats are fitted the dies 18 which are plural sided and longitudinally grooved for engagement with opposite surfaces of a rope or cable 19, said grooves in the dies being of different depth, or struck from different radii so as to fit ropes or cables of different diameters, and the dies being interchangeably fitted in the seat, so that either

of the grooved faces thereof may be exposed for use in clamping an interposed rope or cable.

Extending from the jaws are the arms 20 and 21, of which the latter carries a swinging bolt 22 pivoted as at 23 and fitted with a thumb nut 24 for engagement with a slot 25 in the free end of the arm 20. A washer 26 is preferably interposed between the thumb nut and the arm 20 so as to receive the pressure of the former in forcing the arms toward each other to substantially clamp a cable or rope which is interposed between the jaws.

The connection between the swinging bolt and the arm 21 which carries the same, the pivotal mounting of said bolt being designed to permit of the ready disengagement thereof from the curb or slot in the end of the arm 20 to permit of the separation of the arm to open the jaws, preferably includes a tensioning arm 27 pivoted as at 28 between ears 29 on the arm 21 and having the pivot bolt mounted thereon as indicated, the free inner end of the tensioning arm having connected therewith a tension bolt 29' extending through an opening 30 in the arm 21 and fitted with a thumb nut 31, a washer 32 being interposed between the thumb nut and the outer surface of the arm 21 so as to receive the pressure thereof.

In operation, after the jaws have been disposed upon opposite sides of the rope or cable to be clamped, the arms of the jaws are drawn toward each other until the swinging bolt can be engaged with the curb or slot in the ends of the arm 20, after which the thumb nut may be tightened. After this adjustment additional tension may be applied to the swinging or clamping bolts by the adjustment of the nut on the tension bolt which serves to swing the free end of the tension arm toward the arm 21 and thus by reason of the leverage afforded draw the jaws together with a force which is impossible merely by the tightening of the clamping bolts. In this way a compressive force may be applied through the jaws and their dies to the rope or cable which will entirely provide against any possibility of slipping or loosening.

Having thus described our invention, what we claim is:

1. A rope or cable clamp having pivotally connected jaws provided with operating arms, a swinging clamp bolt carried by one

of the arms for engagement with a curb or slot in the other arm and provided with an adjusting nut, and a tensioning device connecting said clamping bolt with the first named arm, and adjustable to vary the position of the clamping bolt with relation thereto.

2. A rope or cable clamp having pivotally connected jaws provided with operating arms, a clamping bolt carried by one of said arms for engagement with the other arm and having an adjusting nut, and a tensioning device consisting of a tension bar pivoted to the first named arm and having the clamping bolt mounted thereon, and a tension bolt for varying the position of the tension bar with reference to said arm.

3. A rope or cable clamp having pivotally connected jaws provided with operating arms, a swinging clamp bolt carried by one of said arms for engagement with the other

and provided with an adjusting nut, and a tensioning device consisting of a tension bar pivotally mounted upon the first named arm and having the clamping bolt pivotally connected thereto at an intermediate point, and a tension bolt connected with the free end of said tension bar, extending through the first named arm and fitted with an adjusting nut.

4. A rope or cable clamp having pivotally connected dogs provided with operating arms, an adjustable tensioning device carried by one of said arms, and a clamping element carried by the tensioning device for engagement with the other of said arms. 35

In testimony whereof we affix our signatures in presence of two witnesses.

ORAL C. ZUCK.
LEE O. BACON.
